BLOCK SIGNALING SYSTEM FOR
RAILROADS

Robert M. Phinney, Rochester, N. Y., assignor to
General Railway Signal Company, Rochester,
N. Y.

Application August 16, 1935, Serial No. 36,481

12 Claims. (Cl. 246—33)

This invention relates to block signaling systems for single track railways, and more particularly to such a system of the type known as an absolute permissive block system.

- 5 In an absolute permissive block signaling system, the portions of single track between passing sidings are signaled for either direction of traffic, and the same facility and protection for trains following each other through the portions of single track is provided as in a modern signaling system for one direction of traffic only, but trains are prevented from entering the single track portions already occupied by a train or trains moving in the opposite direction. In the usual absolute permissive block system, a series of signal controlling relays associated with each direction of traffic are controlled in tumble down or repeater fashion so that a train entering one end of the single track portion causes the series of signal controlling relays associated with the opposite direction of traffic to tumble down to the other end of the single track portion thereby causing all opposing signals to display a stop indication, and directional stick relays are selected 25 in accordance with the direction of a train progressing through the single track portion which affect the signal control relays associated with the same direction of traffic in the manner to permit following train movements.
- 30 In railway signaling systems, it is essential that all circuits and apparatus should be energized to provide a clear signal indication, as a failure of the energy source, a broken wire or the like then results in a restrictive signal indication thus providing maximum safety of train operation in the event of a failure of signal apparatus or circuits. Consequently in an absolute permissive block signaling system, it is usually necessary to provide signal controlling relays, line circuits and the like 35 which are normally maintained energized while a train is not passing through the associated portion of the railway system in order that upon the entrance of a train, the series of signal controlling relays can be tumbled down or successively deenergized with certainty to affect a stop indication at opposing signals. It will therefore be evident that energy is required in such normally energized systems for the signals and their controlling apparatus at all times except when a 40 stop indication is being displayed, and when primary or storage batteries are employed, it is highly desirable to reduce such energy consumption to a minimum.

In signaling systems employing semaphore wayside signals, a severe sleet storm or freezing

rain may prevent movement of the semaphore arm. Consequently in a signaling system wherein the signals normally display a clear indication, the semaphore arms assume a clear position throughout the majority of the time, so that an abnormal condition usually prevents movement of the semaphore arm from its clear position and a clear indication then exists which possibly may be over an unsafe section of track.

In view of the above and other considerations, 10 it is proposed in accordance with the present invention to provide an absolute permissive block signaling system wherein the energy consumed is reduced to a minimum and yet which affords the usual protection and facility for train movements. 15 More specifically, it is proposed to provide an absolute permissive block signaling system wherein the wayside signals, the signal control relays and line circuits or all the apparatus with the exception of the usual track circuits are normally deenergized while a train is not approaching or traversing the associated portion of the railway system, and which is initiated into operation by an approaching train to provide equal facility and the same degree of signal protection for such 20 train movements as is provided by the usual normally energized systems. It is further proposed to provide a signaling system having the advantages attributed to signals wherein a restricted 25 indication is normally displayed when a train is 30 not approaching such signals.

Other objects, purposes and characteristic features of the present invention will be apparent as the description thereof progresses, during which references will be made to the accompanying 35 drawings, in which:—

Fig. 1 and Fig. 2 show in a diagrammatic and conventional manner one embodiment of the present invention applied to a portion of a railway system. These two figures show adjacent 40 portions of railway track and are intended to be placed end to end with Fig. 2 at the right.

The portion of the railway system shown in the accompanying drawings is divided by insulating joints J into sections or blocks 1 through 7, the 45 blocks 2 and 6 including double track or what is known as passing sidings. In describing the present invention, the apparatus having like functions at the different locations or blocks have been given the same reference letter or letters with a preceding numeral corresponding to the reference number of the associated block. In order to simplify the present disclosure, the signal controlling apparatus and circuits have been shown in detail for one direction of traffic only, 50 55

namely, for the east bound signals SG, it being clear to any one skilled in the railway signaling art that this apparatus is duplicated in a reversed manner for controlling the west bound signals.

5 More specifically, the west bound signals 12SG, 13SG, 14SG, 15SG, 16SG and 17SG are respectively controlled in accordance with approach control and in accordance with traffic conditions in advance in exactly the same way as are the 10 east bound signals 2SG, 3SG, 4SG, 5SG, 6SG and 7SG, respectively. Also, the west bound signals 13SG, 14SG and 15SG are controlled by back contacts of stick relays 5S, 4S and 3S respectively, as the east bound signals 3SG, 4SG and 5SG are controlled by back contacts 47, 36 and 25 of stick relays 15S, 14S and 13S, respectively.

A track circuit of the usual normally energized type is provided at each block by a battery B at one end and a track relay T at the other end, 20 it being understood that this merely represents the usual means for detecting the presence of a train and various center fed or cut section track circuits may be provided as required.

The wayside signals have been conventionally 25 illustrated as the semaphore type, but it is of course understood that other types could be employed such as color light signals of either the individual light type or the movable spectacle type, the methods of adapting the control circuits to the different types of signals being 30 well recognized.

A home relay H is provided for controlling each of the east bound signals SG, which home relay at signals 3SG, 4SG and 5SG are the 35 conventional neutral type and a distant signal controlling relay D of the usual neutral type is provided at each signal. A clearing relay CL employed to initiate operation of the signaling system is provided at each signal location except the signals governing movements into the 40 double track portions such as signals 2SG and 6SG, which CL relays are connected in series with the line circuit control for the D relays at the next signal in the rear.

45 The signals governing movements into the double track portion are provided with home relays 2H and 6H which are arranged in the same manner as the clearing relays CL at the other locations, and the clearing relays CL as 50 well as the two home relays 2H and 6H are provided with two separate windings A and B. It is necessary for a proper operation of the present system to provide a certain relation between the resistance of the windings of the D relays and the windings A and B of relays CL, 2H and 55 6H, or that is the resistance and the ampere-turns of the D relays should be considerably smaller than that of both windings A and B of the CL, 2H and 6H relays, so that when an energizing circuit has been completed connecting windings A and B in series with windings of 60 relay D, the armature of relay D will not be attracted while the armature acted upon by windings A and B will be attracted, and when winding A is shunted the current in this circuit should increase sufficiently to attract the armature of relay D and the energization of winding A alone should retain its armature. For example, the windings of relay D may be approximately 60 ohms, winding A may be 800 ohms and winding B may be 100 ohms.

A directional stick relay S is employed at each of the east bound signal locations except for signals 2SG, 6SG and 7SG which stick relays are associated with east-bound train movements, and

inasmuch as certain signaling circuits associated with east-bound train movements are arranged to check the position of the direction relays associated with the opposite traffic direction, certain of the west-bound direction stick relays, namely relays 13S, 14S and 15S, have been indicated on the drawings. It will be understood that suitable means is to be employed to protect the signaling circuits against improper alignment of the track switches governing movements 10 into the passing sidings which has not been shown in the present disclosure, and that various other expedients well known in the signaling art may be employed as required but which have been herein omitted as they are not necessary for the 15 understanding of the present invention. In the present system, a source of energy is required for energizing the line circuits, the semaphore signals and the like, which may be a suitable local battery, the opposite terminals of which have 20 been merely indicated by the symbols (+) and (-), and it is understood that a common or return line wire (not shown) is required in accordance with the usual practice.

Having now pointed out the essential elements 25 of the system, it is believed that the usefulness and the various interrelated functions and features of the apparatus and circuits of the present embodiment will be more readily understood by further description being given from the stand-point of operation.

Operation

The present system is illustrated in a condition 35 wherein no trains are occupying or approaching the railway system illustrated in the present drawings, and in such a condition, all the apparatus and circuits of the system, with the exception of the track relays T, are deenergized as shown. In the accompanying drawings, it 40 will be understood that a complete signaling system arranged in accordance with the present invention includes many single track portions of which the signaling system for the single track portion shown in Fig. 1 and Fig. 2 is typical, 45 and the signaling circuits for each of the single track portions overlap or extend into the adjacent portion so that in considering a complete train movement, certain conditions must first be assumed as resulting from a train movement 50 through the portion of the railway system adjacent to that herein illustrated.

In other words, in considering an east bound train movement throughout the illustrated single track portion, it will be understood that the 55 control circuits for signal 2SG is the same as that illustrated for signal 6SG and consequently it will be considered when the present east-bound train under consideration enters block 1, the energizing circuit for the home relay 2H is 60 completed by dropping the track relay 1T, although it will be understood later in the description of the initial energization of relay 6H that relay 2H was previously energized by the present train upon entering the portion of the 65 railway system adjacent to the left hand end of the portion illustrated in Fig. 1. The present energizing circuit for relay 2H however, may be traced from (+), front contact 10 of relay 3T, line wire 2LH, front contact 11 of relay 2T, through windings A and B in series of relay 2H, and through back contact 12 of relay 1T to (-).

A circuit is also completed for energizing relays 2D and 3CL while the present east-bound

train is occupying block 1 which may be traced from (+) through windings A and B in series of relay 3CL, line wire 2LD, through the windings of relay 2D, and through back contact 14 of relay 1T to (-). It will be noticed that this circuit includes windings A and B of relay 3CL in series with the windings of relay 2D, and as previously stated, the resistance of winding A is sufficiently high to prevent the flow of sufficient current in this circuit to attract the armature of the low resistance relay 2D, but the same amount of current is effective when flowing through the larger number of turns of windings A and B of relay 3CL to attract its armature.

15 The picking up of relay 3CL then closes an obvious circuit at its front contact 15 over line wire 3LD to, in the same manner, attract the armature of relay 4CL but to allow the armature of relay 3D to remain in its released position, and 20 the picking up of relay 4CL likewise completes an obvious circuit at its front contact 16 to pick up relay 5CL over line wire 4LD but to allow the armature of relay 4D to remain in its released position.

25 In other words, it will be clear that a train occupying section 1 causes the successive picking up of all the clearing relays 3CL, 4CL and 5CL, and the picking up of the last clearing relay 5CL completes an energizing circuit for the home relay 6H which may be traced from (+), front contact 17 of relay 7T, line wire 6LH, front contact 18 of relay 6T, through windings A and B in series of relay 6H, line wire 5LD, through the windings of relay 5D and through front contact 35 19 of relay 5CL to (-). The picking up of the home relay 6H completes an energizing circuit operating the semaphore signal mechanism of signal 6SG to a 45° or caution position, which circuit may be traced from (+), front contact 20 of relay 6H, back contact 21 of relay 6D, 45° control wire 22, through the signal mechanism to (-).

A contact 23 operated by the semaphore mechanism at signal 6SG is now operated to its 45° position to thereby close an obvious shunt circuit around the winding A of relay 6H, which winding A being of comparatively high resistance results in an increase in current through the windings of relay 5D which is effective to attract its armature and the same amount of current through winding B of relay 6H is still effective to retain its armature. The previous picking up of the last clearing relay 5CL also closed a circuit for energizing the home relay 5H from (+), back contact 25 of the west-bound stick relay 13S, line wire 5LH, front contact 26 of relay 5T, through the winding of relay 5H and through front contact 27 of relay 5CL to (-).

60 An operating circuit is now completed for signal 5SG from (+), back contact 28 of relay 5S, front contact 29 of relay 5H, front contact 30 of relay 5D, 90° control wire 31, through the semaphore mechanism of signal 5SG to (-).

65 The signal 5SG is now operated to a 90° or clear position which moves a contact 32 on the semaphore signal mechanism to its 90° position which completes a shunt circuit around high resistance winding A of relay 5CL, thereby increasing the current through relay 4D sufficiently to attract its armature. The previous picking up of relay 5H also completed a circuit for energizing the home relay 4H from (+), front contact 34 of relay 5H, front contact 35 of relay 5CL, back contact 36 of the west-bound stick relay

14S, line wire 4LH, front contact 37 of relay 4T, through the windings of relay 4H to (-).

An operating circuit for signal 4SG is now completed from (+), back contact 39 of relay 4S, front contact 40 of relay 4H, front contact 41 of relay 4D, 90° control wire 42, through the semaphore signal mechanism to (-). The signal 4SG is thereby operated to its 90° or clear position which moves a contact 43 on the semaphore signal mechanism to its 90° position, thereby shunting out winding A of relay 4CL to increase the current in relay 3D sufficiently to attract its armature. The previous picking up of relay 4H completed a pick up circuit for relay 3H from (+), front contact 45 of relay 4H, front contact 46 of relay 4CL, back contact 47 of relay 15S, line wire 3LH, front contact 48 of relay 3T, through the windings of relay 3H to (-).

An operating circuit for the entering signal 3SG is now completed from (+), back contact 50 of relay 3S, front contact 51 of relay 3H, front contact 52 of relay 3D, 90° control wire 53, through the semaphore signal mechanism to (-). The entering signal 3SG is now operated to a 90° or clear position which in a similar manner 25 shunts the high resistance winding A of relay 3CL by a semaphore signal contact 54 to pick up relay 2D. An operating circuit for the signal 2SG is now completed by front contact 55 of relay 2H, energized as previously described, and 30 through front contact 56 of relay 2D to the 90° control wire 57, thereby operating signal 2SG to its 90° or clear position.

It will now be clear that a train upon entering block 1 successively picks up all the clearing 35 relays up to the next-to-the-last signal location in the single track portion, and the picking up of this last clearing relay or relay 5CL energizes the home relay for the next signal in advance to provide a caution signal indication at this point, 40 and the last clearing relay also picks up its associated home relay, which home relay causes the successive picking up of all the rear home relays back to the entrance to the single track portion. It will also be clear that throughout 45 the single track portion, each D or 45° signal control relay is picked up by the operation of the next signal in advance to a caution or a clear position, thus clearing all the wayside signals throughout the single track portion and allowing the system to thereafter function in a manner 50 similar to that of a conventional normally energized system.

When the present east bound train enters block 2, relay 2D is shunted through back contacts 14 and 59 of relays 1T and 2T, and relay 3CL is maintained energized by back contact 59 of track relay 2T, but the distant relay 2D is later deenergized by the picking up of track relay 1T at back contact 14 when the train departs from 60 block 1. However, when the present train departs from block 2 and enters block 3, the clearing relay 3CL is dropped by the picking up of track relay 2T and the consequent opening of its back contact 59, thereby dropping relay 3D at 65 open front contact 15 of relay 3CL, but the next clearing relay 4CL is maintained energized by a back contact 63 of track relay 3T.

It will of course be obvious that the dropping of relay 3T deenergizes the home relay 3H at 70 front contact 48 thereby causing the signal 3SG to operate to its stop position while block 3 is occupied. A contact 60 is provided on the semaphore mechanism of signal 3SG and is closed only while the semaphore arm is moving through 75

an intermediate position for example through its 40° to 30° position and is opened upon reaching its stop position, which contact 60 closes an obvious energizing circuit for the directional stick 5 relay 3S while signal 3SG is moving to its stop position over the line circuit 3LH and through back contact 48 of track relay 3T. A stick circuit for relay 3S is then completed through back contact 61 of relay 3H and stick contact 62 which holds up relay 3S after the semaphore contact 60 has been opened by the completion of the movement of the semaphore arm to its stop position. The clearing relay 4CL is maintained energized by a front contact 64 of the stick relay 15 3S after track relay 3T picks up, and relay 4D is shunted upon the dropping of track relay 4T through back contact 72 and front contact 16.

The entrance of the present train into block 4 deenergizes the home relay 4H, thus causing 20 the signal 4SG to operate to its stop position, and a contact 66 on the semaphore mechanism operates in a manner similar to the previously described semaphore contact 60 at signal 3SG to pick up the stick relay 4S over line wire 4LH 25 and through back contact 31 of track relay 4T, and a stick circuit is thereafter effective to hold relay 4S picked up through back contact 67 of relay 4H and stick contact 68.

The picking up of stick relay 4S now completes 30 an energizing circuit for the rear home signal 3H through its front contact 70 and front contact 46 of relay 4CL which is being held up by the rear stick relay 3S, and the picking up of the rear home relay 3H obviously drops the stick relay 35 3S at open back contact 61 and the dropping of relay 3S in turn releases the clearing relay 4CL at open front contact 64 which is then effective to again deenergize the rear home relay 3H. In other words, the picking up of the stick relay 4S 40 momentarily energizes the rear home relay to restore all of the relays at the rear signal location to their normal deenergized condition.

The dropping of relay 4CL opens the energizing 45 circuit for relay 4D which was previously shunted, but the forward clearing relay 5CL is maintained energized through back contact 72 of track relay 4T, and when the present train departs from section 4, a front contact 69 on the stick relay 4S is effective to still maintain relay 50 5CL picked up. The directional stick relay 5S is of course picked up by the entrance of the train into block 5 through semaphore contact 13 and back contact 26 of track relay 5T and subsequently held up by a stick circuit including 55 back contact 74 of relay 5H and its stick contact 75. The picking up of stick relay 5S then restores the control relays at the rear signal location to their normal deenergized condition by energizing the rear home relay 4H through its front contact 77 and front contact 35 of the clearing relay 5CL, the energization of relay 4H being effective to release the stick relay 4S at contact 60 61, the releasing of relay 4S dropping the forward clearing relay 5CL at front contact 69 and the deenergization of relay 5CL then acting to remove the energization from the rear home relay 4H at front contact 35. The release of relay 5CL opens the energizing circuit for relay 5D which was previously shunted through back contact 78 and front contact 19, but the forward home relay 6H is maintained energized through back contact 78 of track relay 5T.

In order to restore the control relays associated with signal 5SG to their normal deener-

gized condition upon the departure of a train from block 5, a front contact 76 has been provided upon the stick relay 5S which is effective to energize relay 5H even though relay 5CL is deenergized, and the picking up of relay 5H in turn deenergizes the stick relay 5S at back contact 74, the dropping of relay 5S in turn dropping the home relay 5H to restore the control relays at that location to their deenergized condition.

The present train progresses eastwardly through block 6 in a very obvious manner whereupon the clearing of control relays associated with the single track portion joining the right hand end of the portion shown in the accompanying drawings are initiated into operation over the line circuit 6LH shown at the bottom of Fig. 2 in the manner previously described. It will be noticed in the description of the previous train movement that the apparatus at each signal location passed by the train was restored to its normal deenergized condition by picking up the rear home relay H momentarily and inasmuch as it is desirable to reduce the duration of a clear signal indication during such conditions, a back contact of the associated stick relays has been provided in the control circuit for the signals at these locations, whereby the momentary picking up of the home relays under this condition will not immediately energize the associated signal mechanism inasmuch as the stick relays are picked up through a portion of this period.

The manner in which the present system operates to prevent a train movement into the single track portion while an opposing train is occupying such portion may be seen by considering how a west-bound train movement affects the east-bound signal controlling apparatus disclosed in the present drawings. It is obvious that 35 a west-bound train upon entering blocks 6 or 5 does not pick up the clearing relay 5CL so that the home relay 5H cannot be picked up, and as each of the rear home relays includes a front contact of the forward home relay and a front contact of the associated track relay, the home relay 3H cannot pick up and consequently the signal 3SG cannot be operated to a clear position while a west-bound train is occupying the illustrated portion of single track. It will also be obvious that a west-bound train movement does not pick up the east directional stick relays inasmuch as the associated semaphore signal mechanisms are in this case assuming their stop positions before the associated track relays are dropped, thus preventing a completion of the pick up circuits for the stick relays.

The absolute permissive block feature of permitting following train movements in the same direction through the single track portion is provided in the present system by the directional stick relays in accordance with the usual practice. In other words, while the previously considered east-bound train was occupying section 4, the stick relay 4S was picked up as previously described, so that a second east-bound train entering block 1 would pick up the clearing relay 3CL which in turn would pick up relay 4CL, thereby completing a circuit for energizing relay 3H through front contact 70 of relay 4S and front contact 46 of relay 4CL. The home relay 3H thus picking up would operate signal 3SG to its caution position which picks up relay 2D to operate signal 2SG to a clear position and allows the second train to proceed into the single track.

portion. The relay 3D would pick up as soon as the first train enters block 5 to operate signal 4SG to a caution or 45° position and shunt winding A of relay 4CL, thereby operating signal 3SG from its caution to its clear position.

In this manner it will be seen that one train may follow another into the single track portion by first reestablishing the energizing circuits for such clearing relays as have been dropped in the rear of the first train, and the picked up condition of the directional stick relay at the block occupied by the first train then allows the home signal controlling relays in the rear of the train which are associated with the particular direction of travel only to be successively energized. The distant signal controlling relays pick up in the same manner as previously described, or by the operation of the semaphore signal mechanism at the next forward signal location to a caution or clear position. The signal controlling relays are all restored to their normal deenergized condition at each location after being passed by the last train in the same manner as described in connection with the first train movement.

An absolute permissive block signaling system has thus been provided wherein all the signal controlling relays are normally deenergized when a train is not occupying or approaching the associated portion of the railway system, and wherein in the signals normally display a stop or most restricted indication at such times. The advantage of such a system in regard to the saving of the energy ordinarily required in the usual normally energized system to maintain the signal controlling relays energized while a train is not occupying or approaching the associated portion of the railway system is readily apparent. Among the other advantages of the present system is the reduced possibility of displaying a false-clear signal indication by the sticking of a semaphore signal arm, this being due to the fact that the present system provides normally danger signals whereby the sticking of the semaphore arm would ordinarily occur in its danger position thereby providing a restricted but a safe signal indication.

In describing the present invention, attention has been directed to one specific embodiment thereof, without attempting to point out the various alternate or optional features of construction, or the different organizations or combinations that may be employed. For example, in the simplified disclosure of the present invention the clearing relays associated with a particular direction of train movements pick up in the rear of a train traveling in the opposite direction, which operation is ordinarily not objectional but if desired certain changes which are considered to be entirely within the ability of anyone skilled in the railway signaling art could be made to prevent this unnecessary relay operation.

In other words, the particular embodiment of the present invention has been selected to facilitate in the disclosure thereof rather than to limit the number of forms which it may assume.

What I claim is:—

1. In a single track railway signaling system, wayside signals governing traffic in each direction over the single track, a normally de-energized clearing relay associated with each signal, means successively energizing the clearing relays associated with signals governing traffic in either direction upon the approach of a train traveling in such direction, a normally de-energized home signal controlling relay for each signal, means depend-

ent upon traffic conditions for successively energizing the home relays for signals governing traffic in either direction upon the energization of the last clearing relay associated with such traffic direction, a normally de-energized distant signal controlling relay for each signal, and means including the energizing circuits for the clearing relays for controlling each distant relay in accordance with the condition of the next forward wayside signal. 5

2. In a single track railway signaling system, wayside signals governing traffic in each direction over the single track, a normally de-energized clearing relay associated with each signal, means successively energizing the clearing relays 10 15 associated with signals governing traffic in either direction upon the approach of a train traveling in such direction, a normally deenergized home signal controlling relay for each signal, means dependent upon traffic conditions for successively 20 energizing the home relays for all of the signals governing traffic in either direction upon the energization of the last clearing relay associated with such traffic direction, a normally de-energized distant signal controlling relay for each 25 signal, means including the energizing circuits for the associated clearing relays for controlling each distant relay in accordance with the condition of the next forward wayside signal, and directional stick relay means for less than all the 30 signals governing traffic in either direction.

3. In an absolute permissive block signaling system, a semaphore signal, a control relay for the semaphore signal, a track relay for controlling the signal control relay, a directional relay 35 having an energizing circuit including a back contact of the track relay and a contact on the semaphore signal closed only when the semaphore signal assumes a position intermediate the caution and stop position, and a stick circuit for the 40 directional relay including a back contact of the signal control relay.

4. In an absolute permissive block signaling system having semaphore signals, a control relay for each signal, normally energized track relays, 45 an energizing circuit for each control relay including a front contact of the associated track relay and a front contact of the control relay for the next forward signal, a directional stick relay associated with each signal, and an energizing 50 circuit for each directional relay including said front contact of the control relay for the next forward signal, a back contact of the associated track relay and a contact closed only during transit of the associated semaphore signal between its caution and stop positions. 55

5. An absolute-permissive-block single track signaling system comprising, signals for governing traffic in one direction through a single track section, signals for governing traffic in the opposite direction through said single track section, a home relay for each signal, a normally open energizing circuit for each home relay including a front contact of the home relay next in advance, a directional stick relay for each signal which if energized closes a contact in the energizing circuit for the home relay next in the rear, and means for sequentially energizing the home relays governing traffic in a particular direction when a train moving in that direction approaches 60 said single track section. 65

6. An absolute-permissive-block single track signaling system comprising, signals for governing traffic in one direction through a single track section, signals for governing traffic in the opposite direction, 70

site direction through said single track section, a home relay for each signal, a normally open energizing circuit for each home relay including a front contact of the home relay next in advance, a clearing relay for each signal location, a normally open energizing circuit for each clearing relay controlled through a front contact of the clearing relay for the next signal in the rear, means responsive to a train approaching said section in one direction for causing successive energization of the signal clearing relays governing that direction of traffic, and means responsive to the energization of the last signal clearing relay providing no train has entered the opposite end of said single track section for causing successive energization of the home relays governing signals for said one direction, whereby the approach of a train in one direction toward said single track section causes the home relays governing the signals for said one direction to be successively picked up starting with the home relay at the exit end of said section for said one direction of train travel.

7. An absolute-permissive-block single track signaling system comprising, signals for governing traffic in one direction through a single track section, signals for governing traffic in the opposite direction through said single track section, a home relay for each signal, a normally open energizing circuit for each home relay including a front contact of the home relay next in advance, and means responsive to a train approaching said section in one direction providing no train is approaching said section from the opposite direction for causing successive energization of said home relays starting with the home relay at the exit end of said section for said one direction of train travel.

8. An absolute-permissive-block single track signaling system comprising, signals for governing traffic in one direction through a single track section, signals for governing traffic in the opposite direction through said single track section, a home relay for each signal, a normally open energizing circuit for each home relay including a front contact of the home relay next in advance, means responsive to a train approaching said section in one direction providing no train is approaching said section from the opposite direction for causing successive energization of said home relays starting with the home relay at the exit end of said section for said one direction of train travel, and means for causing the second signal to the rear of a train moving through said section to indicate caution upon entrance of a following train into said section.

9. An absolute-permissive-block single track signaling system comprising, signals for governing traffic in one direction through a single track section, signals for governing traffic in the opposite direction through said single track section, a home relay for each signal, a normally open energizing circuit for each home relay including a front contact of the home relay next in advance, means responsive to a train approaching said section in one direction providing no train is approaching said section from the opposite direction for causing successive energization of said home relays starting with the home relay at the exit end of said section for said one direction of train travel, and means including a directional stick relay for each signal for causing the second signal to the rear of a train moving through said

section to indicate caution upon entrance of a following train into said section.

10. In an absolute-permissive-block signaling system, the combination with a single track section connecting two double track portions, signals located at intervals through said section for governing traffic in one direction through said section, signals located at intervals through said section for governing traffic in the opposite direction through said section, a home relay for each signal, a directional stick relay for each signal, a normally open circuit for each home relay including a front contact of the next home relay in advance and a back contact of a directional stick relay associated with a signal for governing traffic in the opposite direction, and means responsive to a train approaching said section in one direction effective only if there is no train approaching said section from the opposite direction for causing successive energization of the home relays governing signals for governing traffic in said one direction starting with the home relay at the exit end of said section for said one direction of travel.

11. In an absolute-permissive-block signaling system, the combination with a single track section connecting two double track portions, signals located at intervals through said section for governing traffic in one direction through said section, signals located at intervals through said section for governing traffic in the opposite direction through said section, a home relay for each signal, a directional stick relay for each signal, a normally open circuit for each home relay including a front contact of the next home relay in advance and a back contact of a directional stick relay associated with a signal for governing traffic in the opposite direction, means responsive to a train approaching said section in one direction effective only if there is no train approaching said section from the opposite direction for causing successive energization of the home relays governing signals for governing traffic in said one direction starting with the home relay at the exit end of said section for said one direction of travel, and means including said directional stick relays for causing the second signal to the rear of a train moving through said section to assume a caution position when a second train follows such train into the said single track section.

12. An absolute-permissive-block single track signaling system comprising, signals for governing traffic in one direction through a single track section, signals for governing traffic in the opposite direction through said single track section, a home relay for each signal, a normally open energizing circuit for each home relay including a front contact of the home relay next in advance, a directional stick relay for each signal which if energized closes a contact in the energizing circuit for the home relay next in the rear, a clearing relay for each signal having an energizing circuit including a front contact of the clearing relay for the next signal in the rear, said clearing relays for one particular direction of traffic when energized permitting energization of the home relays for that direction of traffic, and means for successively energizing said clearing relays for a particular direction of traffic when a train moving in that direction approaches said single track section.

ROBERT M. PHINNEY.
